GOLF TEE AND SWING PRACTICE DEVICE

Harry A. Smith, Oak Hill, N.Y.

Application October 17, 1958, Serial No. 53,023

Term of patent 14 years

(Cl. D34—5)

Fig. 1 is a plan view showing my design for a golf tee and swing practice device; and

Fig. 2 is a side edge elevation of the design with a portion thereof broken away in the tee area for illustrative purposes.

I claim:

The ornamental design for a golf tee and swing practice device, as shown.
